UNITED STATES PATENT OFFICE

CHARLES E. HOWARD, OF YPSILANTI, MICHIGAN

ADVERTISING DEVICE

Application filed April 24, 1929. Serial No. 357,760.

My present invention has reference to an illuminated advertising device or sign, and my object is the provision of a device for this purpose which includes an illuminated revoluble tubular member that has set in circumferential and longitudinally arranged series of openings therein differently colored glasses whose outer faces are cut to correspond in a general way with the facets of a diamond and for reflecting light there-through onto a concaved reflective surface arranged to the rear of the cylinder, together with a novel effect produced by the multiplicity of varying colored light rays reflected from the device will attract the attention of the public thereto.

A further object is the provision of an advertising device which is especially adaptable for use as a barber's pole, but, of course, susceptible to other uses in which the rays of light from the device are directed through the cut-out letters indicating the name and business of the owner of the device.

To the attainment of the above broadly stated objects and many others which will present themselves as the nature of the invention is better understood, the invention also consists in other novel features of construction, combination and operative association of parts, one satisfactory embodiment of which is disclosed by the accompanying drawings.

In the drawings.

Figure 1 is a front elevation of the invention.

Figure 2 is a sectional view approximately on the line 2-2 of Figure 1.

Figure 3 is a top plan view of the invention.

Figure 4 is a transverse sectional view therethrough.

As disclosed by the drawings, my invention contemplates the employment of a hollow substantially rectangular base 1, which, however, is closed by a top plate 2. In the base 1 there is a motor, broadly indicated by the numeral 3. This motor may be of the electric type, but in the showing of the drawings the same is spring wound and is provided with a winding handle 4 that extends

through one side of the base. The drive shaft 6 of the motor 3 extends through a bearing opening in the top 2 of the base 1 and secured to the closed bottom 8 of a cylinder 9. There may, of course, be anti-frictional bearings between the top 2 and the base 8 of the cylinder. The cylinder is of a considerable height and has its top closed by a dome-like plate 10. The cylinder, throughout its length, is provided with series of circumferentially arranged equidistantly spaced openings which are round and in each of these openings there is seated differently colored translucent glass or other discs 11. The outer face of each of the discs is cut to represent the facets of a diamond as indicated by the numeral 12.

Supported on the top 2 of the base 1, to the rear of the cylinder 9 there is a vertically arranged semi-cylindrical plate 13, and the inner and concaved face of this plate has cemented or otherwise secured thereon any desired number of reflective plates or surfaces 14 which have their ends contacted. The plates 14 may be in the nature of molds and the edges of each of the plates are beveled, as at 15.

The dome 10 of the cylinder 9 is provided with an extension whose outer edge is rounded or flanged and contacting with the semi-cylindrical plate 13, and this extension is formed with an opening 17. The opening is covered by an upper angle or curved plate 18 which is secured to a holder 19 that is arranged transversely over the dome-like top 10 for the cylinder 9. In this holder 19 there is arranged a sign plate 20. The plate 20 may be of glass, metal or pasteboard and when of glass there is painted thereon the name and business of the owner of the sign but when of paper or metal the letters of the owner and his business are cut out of such plates.

Set in the dome-shaped top 10, directly to the rear of the frame 19 there is a lamp bulb 21, the socket 22 of which being removable but fixed in the said opening. The cord for the said bulb is indicated by the numeral 23 and also is directed through a small open-

ing in the top or shield 18 to a suitable source of electric supply such as a house current.

The flanged outer edge 24 of the top 10 has fixed thereto depending pendants 25 which are also of differently colored translucent material such as glass.

The motor is timed so as to slowly revolve the cylinder. The rays of light from the bulb in the cylinder will be directed through all of the translucent discs 11, certain of which will be directed outwardly of the sign and others against the transparent plates 14, so that prismatic rays of light will be directed outwardly from the sign along the sides of the cylinder, while other varying colored lights will be directed through the cylinder. In addition to this varying colored lights are directed through the opening 17 between the shield and the top 10 of the cylinder, such lights being, of course, directed through the sign plate 20. The pendants 25 add to the pleasing illuminating effect of the sign and the simplicity of the construction, the operation and many advantages thereof will, it is thought, be understood and appreciated by those skilled in the art without further detailed description. Obviously I do not wish to be restricted to the precise details herein set forth and, therefore, hold myself entitled to make such changes therefrom as fairly fall within the scope of what I claim.

Having described the invention, I claim:

1. In an illuminated sign, a base having a motor therein, a cylinder on the top of the base to which the driven shaft of the motor is fixed, said cylinder, throughout its length, being provided with spaced series of circumferential openings, different colored translucent discs seated in said openings and having their outer faces cut to provide facets, a flanged cover arranged over the top but free from connection with the cylinder, a semi-cylindrical member resting on the base and arranged to the rear and to the sides of the cylinder and held spaced from the cylinder by the flanged cap, a vertically arranged reflective surface on the inner face of the semi-cylindrical member, a sign plate on the top carrying a sign provided with open letters, a plate between the top of the sign and the rear of the cover, said cover, opposite the reflective surface having an opening therethrough and a lamp bulb supported on the cover and arranged in the cylinder.

55 2. In an illuminated sign, a base having a motor therein, a cylinder on the top of the base to which the driven shaft of the motor is fixed, said cylinder, throughout its length being provided with spaced series of circumferential openings, different colored translucent discs seated in said openings and having their outer faces cut to provide facets, a flanged cover arranged over the top but free from connection with the cylinder, a semi-cylindrical member resting on the base and ar-

ranged to the rear and to the sides of the cylinder, and held spaced from the cylinder by the flanged cap, a vertically arranged reflective surface on the inner face of the semi-cylindrical member, a sign plate on the top carrying a sign provided with open letters, a plate between the top of the sign and the rear of the cover, said cover, opposite the reflective surface having an opening therethrough, a lamp bulb supported on the cover and arranged in the cylinder and the flanged outer edge of the top having translucent pendants loosely supported thereon.

In testimony whereof I affix my signature.
